UNITED STATES PATENT OFFICE.

JOHN THOMAS GOSLINE, OF VANCOUVER, BRITISH COLUMBIA, CANADA.

SIDE-DRESSING ATTACHMENT FOR SAW-FILING MACHINES.

1,243,731.

Specification of Letters Patent. Patented Oct. 23, 1917.

Application filed July 6, 1916. Serial No. 107,838.

To all whom it may concern:

Be it known that I, JOHN THOS. GOSLINE, a citizen of the United States, residing at Vancouver, in the Province of British Columbia and Dominion of Canada, have invented certain new and useful Improvements in Side-Dressing Attachments for Saw-Filing Machines; and I do hereby declare the following to be a full, clear, and 10 exact description of the invention, such as will enable others skilled in the art to which it appertains to make and use the same.

This invention relates to an attachment for circle saw filing machines, and the primary 15 object of the invention is to provide an attachment, which is applicable for detachable mounting upon the slide of a saw filing machine, which is commercially known as the Coval No. 55, or which may be attached 20 to any similar saw filing machine.

An object of the invention is to provide a device of this nature, which will dress or file the sides of the teeth of the saw, making all of the teeth of uniform width.

25 A further object of this invention is to provide a side dressing attachment as specified which includes a pair of pivotally mounted brace controlled jaws, and means for adjusting the position of the outer active 30 or operative ends of the jaws, for regulating their engagement with the sides of the teeth of a circle saw and to mount files in the outer inner faces of said jaws for dressing the sides of a circle saw's teeth.

35 With the foregoing and other objects in view this invention consists in such novel features of construction, combination and arrangement of parts as will be hereinafter more fully described, illustrated in the accompanying drawings and claimed.

40 In describing the invention in detail reference will be had to the accompanying drawings wherein like characters designate like and corresponding parts throughout the several views, and in which:—

45 Figure 1 is a side elevation of the improved side dressing attachment showing the same applied.

Fig. 2 is a top plan view of the attachment.

50 Fig. 3 is a horizontal section having the top or cover plate removed.

Fig. 4 is a vertical section through the attachment, and

Fig. 5 is a detail perspective of one of 55 the pivoted jaws of the attachment.

Referring more particularly to the drawings, 1 designates a slide which is an extension on the original slides of a saw filing machine, and 2 designates the side dressing 60 attachment as an entirety. The side dressing attachment includes a cross head structure 3. The cross head structure 3 is composed of side plates 4 and a bottom plate 5. One of the side plates 4 is provided with a 65 hand screw 6, which is provided for clamping engagement with the slide 1 for holding the cross head at adjusted positions upon the slide.

A plate 7 is mounted upon top of the 70 cross head structure 2 and it is provided with upstanding sides 8 which are cut away as shown at 9. A pair of jaws 10 and 11 are pivotally connected as shown at 12 to the upper surface of the plate 7, and they 75 extend the length of the plate and project a short distance beyond the outer end of the same. The jaws 10 and 11 are provided with cut out portions 13 formed in their inner facing surfaces, in which are placed files 14. 80 Clamping plates 15 are attached to the outer end of the jaws 10 and 11 by suitable set screws 16 and they are provided with recesses 17, which receive the forward inner corners of the files for clamping the files 85 securely in the recesses 13 and holding them connected to the jaws 10 and 11. The jaws 10 and 11 have their inner edges cut away, adjacent their rear pivoted ends as shown at 19. A flat spring 20 is positioned between 90 the facing edges of the jaws 10 and 11 and its forward end engages the shoulders 21 formed by the cut out portion 19. The spring 20 tends to force the jaws 10 and 11 outwardly away from each other. The jaws 95 10 and 11 are moved inwardly toward each other, by hand screws 22 and 23 which are rotatably carried by the upstanding sides 8 of the plate 7, and extend through bosses 24 which are formed upon the ends of the 100 upstanding sides.

The plate 7 is cut away as shown at 25 so as to permit a saw to extend into the same so that the teeth of the saw indicated by the

numeral 26 in Fig. 1 of the drawings will be properly engaged by the files 14. An upstanding boss 27 is formed upon the plate 7 and is provided with a screw threaded bore 28 into which the lower end of a hand screw 29 is threaded. The hand screw 29 extends through a cover plate 30, which cover plate has its forward edges connected to the upstanding sides 8 of the plate 7 by set screws 10 as shown at 31. The hand screw 29 is provided for forcing the rear end of the cover plate 30 downwardly into firm engagement with the upper surfaces of the jaws 10 and 11 for securely holding the jaws in adjusted position. The cover plate 30 is provided with a cut out portion 32 formed in its forward edge which conforms to the shape of the cut out portion 25 and serves an analogous purpose.

20 Fingers 33 and 34 are connected to the outer edges of the forward ends of the jaws 10 and 11 and extend outwardly therefrom. The fingers 33 and 34 are preferably constructed of resilient metal and have their outer ends curved as shown at 35, to provide a rounded surface for engaging the sides of a circle saw blade, as clearly shown in Fig. 1 of the drawings. The fingers exert a tension on the saw blade and tend to hold the edge of the same firmly as it passes through the files 14 and in alinement with the files.

25 A second cover plate 40 is mounted over the rear pivoted end of the jaws 10 and 11 and is attached to the rear portions of the upstanding sides 8 by set screws 41.

30 The jaws 10 and 11 are provided with cut out portions 36, which are adapted for receiving the lug or boss 27 when the saws are in a closed position.

35 From the foregoing description taken in connection with the accompanying drawings, the advantages of construction and of the method of operation of the improved slide dressing attachment for saw filing machines will be readily apparent to those skilled in the art to which this invention appertains, and while in the foregoing description, the principle of the operation of this invention has been described together 40 with various features of construction, it is to be understood that certain minor features of construction, combination and arrangement of parts may be altered to suit practical conditions provided such alterations are comprehended within the scope of what is claimed.

45 What is claimed is:—

1. In a side dressing attachment for saw filing machines, the combination with a 50 slide, of a cross head structure adapted for sliding movement upon said slide, means for holding said cross head structure in adjusted position upon the slide, a pair of pivotally mounted jaws carried by said cross head structure, saw teeth dressing members 55

carried by the inner edges of the outer ends of said jaws, means for normally holding said jaws outward from each other, and means for moving the jaws toward each other and for holding the same in an adjusted position. 70

2. In a side dressing attachment for saw filing machines, the combination with a slide, of a cross head structure adapted for 75 sliding movement upon said slide, means for holding said cross head structure in adjusted position upon the slide, a pair of pivotally mounted jaws carried by said cross head structure, saw teeth dressing members carried by the inner edges of the outer ends 80 of said saw, a flat spring positioned intermediate said jaws and engaging the jaws for moving them outward from each other, and means for moving the jaws toward each other and for holding the same in adjusted 85 position.

3. In a side dressing attachment for saw filing machines, the combination with a slide, of a cross head structure adapted for 90 sliding movement upon said slide, means for holding said cross head structure in adjusted position upon the slide, a pair of pivotally mounted jaws carried by said cross head structure, means for adjusting the jaws toward each other, and side teeth 95 dressing members detachably carried by the inner edges of said jaws.

4. In a side dressing attachment for saw filing machines, the combination with a slide, of a cross head structure adapted for 100 sliding movement upon said slide, means for holding said cross head structure in an adjusted position upon the slide, a pair of pivotally mounted jaws carried by said cross head structure, means for adjusting 105 the jaws toward each other, said jaws being provided with cut out portions on their inner faces adjacent the forward edges thereof, files positioned in said recesses, and clamping plates secured to the forward 110 edges of said jaws, for receiving the forward corner of the files for holding the same in position on said jaws.

5. In a side dressing attachment for saw filing machines, the combination, with an 115 ordinary saw filing machine slide, of a cross head structure slidably mounted upon said slide, means for holding said cross head structure in various adjusted positions on said slide, a pair of jaws pivotally carried 120 by said cross head structure, files carried by the outer free ends of said jaws and adapted for engagement with the sides of the saw teeth, and hand screws carried by said cross head structure and engaging said jaws for 125 adjusting the position of the jaws and holding them in adjusted position, resilient fingers attached to the outer edges of the free end of said jaws and extending outwardly therefrom, said fingers having their outer 130

ends curved for providing rounded saw engaging surfaces.

6. In a side dressing attachment for saw filing machines, the combination, with an ordinary saw filing machine slide, of a cross head structure slidably mounted upon said slide, means for holding said cross head structure in various adjusted positions on said slide, a pair of jaws pivotally carried by said cross head structure, files carried by the outer free ends of said jaws and adapted for engagement with the sides of the saw teeth, and hand screws carried by said cross head structure and engaging said jaws for adjusting the position of the jaws and holding them in adjusted position, resilient fin-

gers attached to the outer edges of the free end of said jaws and extending outwardly therefrom, said fingers having their outer ends curved for providing rounded saw engaging surfaces, a cover plate carried by said cross head structure, and means for clamping said cover plate in firm engagement with the upper edges of said pivoted jaws.
